UNITED STATES PATENT OFFICE.

WIRT W. WALTON, OF NEW YORK, N. Y.

DESIGN FOR AN AUTOMOBILE-BODY.

51,127.

Specification for Design.

Patented Aug. 7, 1917.

Application filed April 7, 1917. Serial No. 160,580. Term of patent 7 years.

To all whom it may concern:

Be it known that I, WIRT W. WALTON, a citizen of the United States, and a resident of New York, borough of Manhattan, in the county and State of New York, have invented a new, original, and ornamental Design for Automobile-Bodies, of which the following is a specification, reference being had to the accompanying drawing, forming a part thereof.

Figure 1 is a top plan view;
Fig. 2 is a side elevation; and
Fig. 3 is a rear end view.

I claim:

The ornamental design for an automobile body, as shown.

WIRT W. WALTON.
